HAT FORMING MACHINE

Robert M. Cuming, New York, N. Y., assignor
to M. A. Cuming & Co., Inc., New York, N. Y.

Application August 24, 1935, Serial No. 37,689

2 Claims. (Cl. 223—13)

This invention relates to new and useful improvements in a hat forming machine.

The invention has for an object the construction of a machine as mentioned which is characterized by a top block having a flange portion and a central expandable crown portion cooperative with a bottom block in a novel manner.

More particularly, the invention contemplates the provision of small cam elements upon the flange portion of the top block cooperating with cutout portions on the bottom block so that there is an aligning tendency as the blocks are forced together to more efficiently form the hat.

Another object of the invention proposes another construction for regulating the distance between the top and bottom blocks.

A further object of the invention is a novel construction for protecting the expandable crown portion from heating devices for heating the blocks.

Still further the invention proposes a novel construction wherein the expandable crown portion is limited in its motion.

A still further object of the invention is to mount one of the blocks resiliently in a manner so that the small cam elements may move the blocks into perfect alignment when the blocks are engaged with each other.

Another object is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a machine constructed according to this invention.

Fig. 2 is a fragmentary perspective view of a portion of Fig. 1 showing the bottom block in position beneath the top block.

Fig. 3 is a view similar to Fig. 2 but showing the top and bottom blocks engaged.

Fig. 4 is a rear elevational view of Fig. 4.

Fig. 5 is a plan view looking in the direction of the line 5—5 of Fig. 4.

Fig. 6 is a sectional view taken on the line 6—6 of Fig. 5.

Fig. 7 is a sectional view taken on the line 7—7 of Fig. 4.

Fig. 8 is a sectional view taken on the line 8—8 of Fig. 7.

Fig. 9 is a view similar to Fig. 6 but illustrating another embodiment of the invention.

Fig. 10 is a fragmentary vertical sectional view 5 taken on line 10—10 of Fig. 4.

Fig. 11 is a vertical sectional view taken on the line 11—11 of Fig. 10.

The hat forming machine, according to this invention, comprises a frame 10, a carriage 11 slidably mounted on the frame, a top block 12 mounted on the carriage, a bottom block 13 adjustably mounted on the frame and adapted to be placed beneath said top block and said top block having a flange portion 14 and a central 15 inflatable or expandable crown portion 15. A means is provided on the flange 14 and on the bottom block for alignably clamping the hat, and a means is provided for inflating or expanding said crown portion to suitably form the hat. 20

More particularly, the frame 10 comprises a pair of vertical posts 10a mounted on a base structure 17. The carriage 11 has several bushings 18 slidably engaging on the posts 10a. A means is provided for moving the carriage up and down 25 on the frame. This means consists of a pair of links 19 pivotally mounted at the top ends upon a cross member 20 mounted between the posts 10a.

The lower ends of the links 19 pivotally connect with other links 20 which are mounted 30 on a shaft 21 rotative in lugs 22 mounted on the carriage 11. A handle 23 is rotative upon one of the cams 21' of the shaft 21 and is secured to link 20. The handle 23 may be turned so as to cause the links 19 and 20 to assume positions in end alignment with each other. This is the closed position of the machine and is illustrated in Fig. 3. It should be noted that the handle 23 is then completely lowered and that the top and bottom blocks are in engagement 40 with each other. The carriage 11 is counterbalanced by a mechanism including cables 24 which engage pulleys 25 mounted upon brackets 26 from the cross piece 20. The cables connect with a counterweight 27. 45

An auxiliary handle 23' is secured to shaft 21 so that after handle 23 is completely lowered, an additional pressure may be applied by lowering carriage 11 by the rotation of cams 21'. This additional pressure is desirable when the hat is 50 made of certain soft material.

The top block 12 comprises a hub portion 29 supported by several studs 30' connected with the carriage 11. These studs serve to fixedly hold the top block. The hub portion 29 has a hollow 55

cylindrical core 30 extending into the expandible crown portion 15. The upper edges of the crown portion 15 are clamped between the hub 29 and an annular member 31 which is attached 5 to the hub. The flange portion 14 has a shoulder 33 upon which the annular member 31 is attached. The hub portion 29, the annular member 31 and the edge of the crown portion 15 all are disposed within the recess in the block 12 10 which forms the shoulder 33.

The means on the flange portion and on the bottom block for alignably clamping the hat comprises several cams 37 projecting from the flange portion 14 and engageable in cam recesses 38 15 formed in the bottom block. The arrangement is such that when the blocks are engaged with each other the cams 37 will engage the recesses 38 and slightly twist or move the bottom block relative to the top block. This motion is a very small 20 amount but is sufficient to insure the proper aligning of the blocks and hat between the blocks.

The means for expanding the expandible crown portion 15 comprises a hydraulic tank 40 having an air inlet 41 above the hydraulic which is connected with a valve 42 operated by the handle 43 25 and controlling a supply of compressed air through the supply pipe 44. A pressure gauge 45 is arranged between the valve 42 and the tank 40 to indicate the pressure within the tank. A pressure release valve 46 is connected laterally 30 with the inlet 41 and connects with a discharge funnel 47. A pipe 48 from the bottom of the tank 40 connects with a flexible pipe 49, in turn connected with a rigid pipe 50 mounted on the top 35 block. This pipe 50 terminates in an end 51 extending axially through the hollow cylindrical portion 30 of the hub. The pipe 50 serves as a stop to limit the upward motion of the crown portion 15 when vacuum is formed with the cylindrical portion 30. During the operation of the machine the expanding portion 15 is expanded by forcing the hydraulic into the portion 15 and thereafter it is contracted by withdrawing the hydraulic.

A heater 55 encircles the block 12 and is adapted to supply the heat necessary. A feature of the invention resides in the fact that the heat or flame of the heater 55 cannot reach the upper edge of the material of the crown portion 15, 50 since this edge is partitioned from the flame by flange 12' of block 12. In prior constructions the edges of the crown portion are directly exposed to the flames or the heat from the heater 55.

The bottom block rests freely on a bed element 57 supported by several rollers upon tracks 55 58, supported upon the frame of the machine. The bed 57 is provided with a handle 59 by which it may be manually moved. The tracks 58 extend to the front so that the bed 57 may be drawn 60 forward and the hat easily removed from the bottom block. Or, the bed 57 may be pushed completely rearward to a position in which the bottom block is aligned with the top block. The bottom block includes a forming element 60 freely resting on the bed 57. This forming element 60 is of a shape adapted to receive a hat and support the brim and crown. The block 13 is formed 65 with the recesses 38 as previously described (see Fig. 6). The bottom block is also heated. There is a channel construction 61 in the bed 57 through 70 which the steam may be supplied for the heat. There is also a gas pipe heater 62 mounted upon the lower portion of the bed 57. Also, an electrical heater 63 is provided on the lower portion

of the bed. Thus, there is a selection of heating means.

The operation of the device is as follows:—

The top and bottom blocks, 12 and 13 respectively, are brought up to the proper temperature 5 by the operation of the heater for the blocks. A hat may then be placed on the bottom block 13 with the crown engaging into the crown portion of the block, and the brim resting on the brim portion. The bottom block is then pushed inward to a position beneath the top block. The handle 23 is moved downward so that the top block is brought into engagement to clamp the hat against the bottom block. During the initial stages of the clamping operation the cam 15 projections 37 engage the cam recesses 38 so that there is a slight twisting or moving to properly align the blocks, then auxiliary adjustment may be made by rotating handle 23', thus actuating cams 21' and lowering carriage 11 to the 20 desired position. The valve 43 is then operated to cause the hydraulic to expand the expandible crown portion 15 under suitable pressure to operate to form the hat. The valve 42 is operated to cause the hydraulic to flow back to the tank 40 25 so that the crown portion 15 is collapsed and is free from the hat. The top block is then raised by the proper operation of the handle 23, the bottom block 13 is moved to the front, and the hat is removed.

In the form of the invention illustrated in Fig. 9 a means is shown for resiliently holding the block 13' in a normal position. This contrasts with the prior construction where the block is free to move slightly laterally. The resilient means consists of several springs 57a mounted on the bed 57 and engaging against the sides of the crown portion of the forming element 60. With this construction the forming element, when free, will always be held in the same position. When 40 the top and bottom blocks engage each other, the cams 37 will engage the cam recesses 38 to properly align the blocks.

A further advantage gained by the relative shifting of the blocks when they assume their 45 operative clamping position is that the shift will have a tendency to make the blocks firmly grip the brim of the hat so that it is held sufficiently tight to prevent any motion when the crown portion of the hat is placed under pressure by the expansion of the crown element 15.

While I have illustrated and described the preferred embodiment of my invention, it is to be understood that I do not limit myself to the precise construction herein disclosed and the right 55 is reserved to all changes and modifications coming within the scope of the invention as defined in the appended claims.

Having thus described my invention, what I claim as new, and desire to secure by United States Letters Patent is:—

1. A hat forming machine, comprising a frame, a carriage slidably mounted on said frame, a top block mounted on said carriage, said top block having a flange portion and a central inflatable 65 crown portion, a bed adjustably mounted on said frame below said carriage, a bottom block supported in said bed, means in said top and bottom blocks for alignably clamping the brim of a hat, means for inflating said crown portion, and resilient means for holding said bottom block normally beneath said top block.

2. A hat forming machine, comprising a frame, a carriage slidably mounted on said frame, a top block mounted on said carriage, said top block 70

having a flange portion and a central inflatable crown portion, a bed adjustably mounted on said flange and adapted to be placed beneath said top block, a bottom block adapted to be engaged within said bed, means on said flange portion and bottom block for alignably clamping the brim of a hat, means for inflating said crown portion, said bottom block resiliently held in normal position

for allowing slight lateral motion when the blocks are engaged and means for resiliently holding said bottom block, said means comprising several leaf springs mounted on the bottom of said bed and extending vertically between said bed and bottom block.

ROBERT M. CUMING.
